UNITED STATES PATENT OFFICE.

AMBROSE KOWASTCH, OF BERLIN-CHARLOTTENBURG, GERMANY.

PRIMER FOR LIQUID-AIR CARTRIDGES.

Application filed July 19, 1920. Serial No. 397,558.

(GRANTED UNDER THE PROVISIONS OF THE ACT OF MARCH 3, 1921, 41 STAT. L., 1313.)

To all whom it may concern:

Be it known that I, AMBROSE KOWASTCH, of Berlin-Charlottenburg, Leibnizstr. 78, Germany, have invented a certain new and 5 useful Primer for Liquid-Air Cartridges, of which the following is a specification.

The present invention relates to a fuse or an ignitor and a method of ignition for blasting charges, when employing liquefied 10 gases. The invention consists first, in saturating the fuse or ignitor with or without a cartridge in immediate proximity, or in front of the bore-hole, in order to bring about and to increase the initial effect, secondly, in order to obtain a stronger and 15 more intense blasting effect, in making the tube of the igniting device of a case or shell of a solid and resistant material, and in providing it with one or several apertures 20 or holes, whereby an ordinary fuse or ignitor, or like priming composition, may be combined with a fuse saturated with liquefied gases. In case the ignitor is saturated inside the borehole, the less skillful workman or miner may happen to fail in introducing and supplying the liquefied gases 25 in such a faultless way to answer all the requirements of a perfect practice. By the present improved method, however, the way 30 of saturating or impregnating the ignitor or priming composition is considerably quicker, safer and more reliable, and in the preparing and finishing of the blasting charge or the cartridge, when they are saturated outside the borehole, is much easier 35 and more simple. Outside the borehole the cartridges without the well known fuse of fulminating mercury, or some similar ignitor, are less dangerous in themselves, and 40 can be more easily handled. All these advantages mentioned above, are gained by saturating the ignitor or primer with or without a cartridge, outside the borehole. How long and strong the walls of the case 45 or shell of the ignitor or detonating tube must be, will depend entirely on the greater or smaller blasting or bursting properties of the cartridge and must be made accordingly.

50 It will, therefore, answer the purpose best to use iron or any similar solid and resistant material for the tube or shell, and provide its wall with holes or apertures, to

admit the liquefied gases, or facilitate their entrance or else leave the longitudinal seam 55 of the tube open, but in such a way that the contents cannot possibly drop out. Owing to the resistance offered by the solid tough metal, or any similar strong material, the pressure inside the shell can be raised correspondingly, and thus the explosive effect 60 will be increased and enhanced. It is of no importance, whether the igniting contrivance is with or without a cartridge when it gets saturated or soaked.

In the accompanying drawing forming a part of this specification the invention is shown by way of two examples.

Fig. 1 represents an igniter or primer for 70 liquid air.

Fig. 2 the combination of a liquid air igniter or igniting cap with an ordinary igniter.

It quite depends upon the requirements of the practical case in question, whether, a 75 fuse or an ignitor which has not been saturated with a liquefied gas, or also a combination of such a fuse with an ignitor that is saturated with liquid oxygen, may be employed to bring about and realize a better 80 and more effective blasting result, and to act as a compensation for eventually too strong an evaporation of the liquid gas fuse.

According to Fig. 1 in the igniting cap 85 a a carbon carrier b is inserted.

The wall of the cap a is easily pervious for the admittance of the liquefied gases so as to impregnate with the same the carbon carrier b. The ignition can be effected either 90 electrically or by means of a quick match.

In the form of execution shown in Fig. 2 d is an ordinary or ready made igniter or primer which can be used without impregnating with a liquefied gas. This primer d 95 is brought in connection with an igniter e or an igniting cap, which is to be saturated with a liquefied gas.

The ignition is effected by electric igniting wires f or by quick-match.

An igniting cap is in many cases preferable to an igniter proper as the latter does not properly oppose cooling down so that it fails or misses fire.

As for the material of the tube or shell 105 of the igniting fuse, it may be chosen in such

a manner, and of such a kind that, when a loss of oxygen takes place after a certain specified time, the priming composition will no longer be able to transmit the ignition.

5 This circumstance or desired effect, can be regulated by the relative thickness of the material selected.

In most cases, in order to keep the priming composition that is soaked with liquefied gases, for a longer time effective, it will be advisable to perform the impregnating process in such a way that an excess or surplus quantity of liquefied gases is absorbed. This surplus quantity will also 15 replace the eventual losses caused by evaporation.

Having thus described my invention, what

I claim and desire to secure by Letters Patent of the United States is:

1. In a device for blasting with the aid of 20 a liquefied gas, the combination of an ordinary igniting fuse with a fuse adapted to be saturated with a liquefied gas.

2. Ignitor characterized by applying and combining an ordinary ignitor or fuse with 25 another ignitor or primer, or enriched priming device which are respectively saturated with liquefied gases.

In testimony whereof I affixed my signature in presence of two witnesses.

AMBROSE KOWASTCH.
